UNITED STATES PATENT OFFICE.

CHARLES F. BASSETT, OF CHICAGO, ILLINOIS, ASSIGNOR TO CHARLES FAIRCHILD, OF NEW YORK, N. Y.

MECHANICAL CASHIER.

SPECIFICATION forming part of Letters Patent No. 678,218, dated July 9, 1901.

Application filed February 27, 1901. Serial No. 49,165. (No model.)

To all whom it may concern:

Be it known that I, CHARLES F. BASSETT, a citizen of the United States, residing at Chicago, in the county of Cook and State of Illinois, have invented certain new and useful Improvements in Operating Means for Cash-Receptacles of Mechanical Cashiers, of which the following is a specification.

This invention relates to cash-receptacle-operating means for mechanical cashiers; and its object is to provide means whereby a rotary cash-receptacle may be moved forward to lock up the money charged into same by direct action thereon of the operator's hand 10 without the use of a separate key or operating device, while at the same time means are provided for allowing or causing return movement of the receptacle under the control of selecting devices to discharge, deliver, or release the money for making change. In controlling such return movement I employ means tending normally to move the receptacle to discharging position and escapement mechanism, whereby such return movement 25 of any particular receptacle is controlled by the selecting devices.

The invention is herein shown as applied to a mechanical cashier wherein the purchase-keyboard and mechanism connected therewith are of the general type shown in the patent to I. S. Dement and myself, dated February 7, 1899, No. 618,932.

In the accompanying drawings, Figure 1 is a vertical section of a cash-receptacle wheel and the coöperating parts of a mechanical cashier embodying my invention, showing the parts in normal position. Fig. 2 is a similar view showing the parts in operated position and the cash-receptacle being shown in elevation. Fig. 3 is a horizontal axial section of the cash-receptacle wheel.

1 represents a portion of the frame of the machine, and 2' parts of the casing thereof. The cash-receptacle consists of a wheel or drum 3, mounted to turn on a shaft or rod 4, which may be screwed on the frame 1 or otherwise supported. The wheel or drum 3 has pockets 3' to receive the coin and works under a concentric portion 2' of the casing, which 45 acts as a shield to cover the pockets except the pocket or pockets that come opposite or

register with the delivery-opening 5 in the case, this shield extending back, but terminating at a point below the receptacle and within the machine, so as to provide an internal opening through which the money may fall from the pocket by gravity into the interior of the casing and be received by suitable receiving and storing means. (Not shown.) Below the opening 5 is the trough 6 or ledge 6, which receives the money discharged from the receptacle. The pockets 3', it will be understood, will be shaped to properly receive the money, whether coins or bills, that is charged into them, and I prefer to so form and arrange the parts that when any charged pocket is moved back opposite the opening 5 the money therein will be discharged or fall by gravity onto the ledge 6. Within the wheel or drum 3, and 70 preferably inside a drum-shaped hub 3" thereof, is a spring 8, which is connected at one end to the shaft or rod 4 and at its other end engages frictionally with the interior or circumferential wall of the hub 3", so as to exert a continual tendency to turn the cash-receptacle backward—i. e., in the direction of the arrow in Fig. 2.

The form of the pockets shown is especially adapted for bills, it being understood that 80 for coin receptacles would be so arranged or formed as to present narrower pockets.

An escapement lever or detent 10 is pivoted on a rod 11, fixed in the frame 1, and is provided with two teeth or pallets 10' 10", 85 adapted to engage alternately with the ribs or tooth-like portions 3^a of the cash-receptacle intervening between the pockets 3', a spring 12 tending to pull the escapement-detent to position in which its pallet 10 will engage with the cash-receptacle 3. This escapement coöperates with or is controlled by the devices that are controlled by the purchase-keyboard to determine the amount of change to be issued.

I have herein shown only so much of the purchase-keyboard mechanism as is necessary for explanation of this invention, it being understood that such mechanism, including the permutating and selecting devices, 100 may be substantially as set forth in the patent aforesaid. The purchase-keyboard com-

prises several series of keys, one key being shown at 14, with a corresponding tumbler-shaft 15 and selector-bar 16, it being understood that the operation of the key will 5 through the permutating mechanism determine the condition of operativeness of the appropriate selector-bars and also in the case of certain of the keys—for example, the key shown—will effect also the actual operation 10 of the selector-bar by moving said bar to the right. It is also necessary to provide means for controlling the operativeness of the selector-bars from the cash-receptacle, so that operation of any cash-receptacle will cancel 15 out certain selector-bars and determine the amount of change according to the amount paid in. For this purpose I provide a two-armed trigger or pawl 17, pivoted on a fixed rod 18 and having one arm extending into 20 the path of the projections 3^a between the pockets 3' of the cash-receptacle, a stop 9 and spring 13 tending to hold this trigger in the position shown, and the said trigger being provided with a spring-latch 17' to en- 25 gage the receptacle as it is pushed forward, but to permit the receptacle to be moved backward without affecting the trigger. A bar or link 19 connects this trigger with an arm 20' of the permutating-sleeve 20, mounted on rod or shaft 21, which sleeve carries also a wing 22, adapted to engage under the corresponding selector bar or bars, so that when the cash-receptacle is turned in the direction of the arrow in Fig. 1 it will cause the 30 bar 19 to be lifted, rocking the shaft 21 and lifting certain of the selector-bars. The construction of the sleeves on shaft 21 and their wings may be substantially as in the patent aforesaid and the operation thereof is identical. 35

Referring now to the means whereby the rearward movement of the selector-bars 16 affects the operation of the cash-receptacle, an arm or lever 23, which may be called the 40 "selector-lever," is arranged in the rear of each selector-bar, the levers 23 being pivoted on a fixed rod or shaft 24 and being pressed forwardly by a spring 25, so as to bring a lug 23' on each selecting-lever in proximity to the 45 rear end of the corresponding selector-bar, the said lever being stopped in this position by a stop-rod 27. At its upper end the lever 23 carries a hinged block or pivoted pawl 28, which when the lever is pressed back by the 50 selector-bar comes between the tail of escapement or detent lever 10 and a bail or operating frame or lever 29, carried by a shaft 30, which has an operating-handle 31, a loose connection, as by a slot 32 and pin 33, 55 being preferably provided between the shaft 30 and frame-bar or lever 29, so as to enable the handle to have an initial movement to effect other desired operations before the frame or lever 29 is lifted. 60

65 The operation of the machine is as follows: The operator places the cash received into the exposed pocket of the corresponding re-

ceptacle and pushes the receptacle, by direct engagement of his hand therewith, in the direction of the arrow in Fig. 1. As the receptacle rotates the projection 3^a thereof, which in normal position lies to the rear of the pallets 10' 10" of the escapement, will pass over the pallet 10', the escapement rocking in such manner as to allow of this movement. During this movement of the receptacle the same projection thereof passes over the trigger 17 and lifts the link 19, thereby rocking the corresponding permutating-sleeve 20 and lifting certain of the selector-bars, the wing 22 coming to the position shown in dotted lines; so that as the trigger 17 and link 19 drop again the selector-bar does not fall, but rests on this wing, slots 19' being provided in the link 19 to permit of this free return movement of 85 the link and trigger. When the attendant removes his hand from the cash-receptacle, the spring 8 returns it toward normal position, the projection 3^a thereof, which was stopped by the rear pallet 10" of the escapement, riding in this back movement over said pallet and allowing the pallet 10' to again stop the cash-receptacle in a position like that it originally occupied, but one pocket in advance. The attendant then strikes the proper 90 purchase-keys, and as a result certain of the selector-bars—for example, the bar 16 in the drawings—are thrown rearwardly and, engaging with the selector-levers 23, press the pawls or hinged blocks 28 on same between the bail or frame-bar 29 and the escapement 10. It will be understood that at this time the pallet 10" is depressed, but that there is room between it and the frame-bar 29 to enable the block 28 to enter between them. The operator then 95 turns the handle 31 forward, lifting the frame-bar 29 and through such blocks 28 as have been thrown rearward raises also the pallets 10" and depresses the pallets 10' of the escapements for certain of the cash-receptacles, 100 whereupon such receptacles are turned back by their springs 8, and as the handle 31 is returned to normal position the escapement-lever 10 falling back, owing to depression of frame-bar 29 and to withdrawal of the blocks 105 28 from between the escapement-lever and the frame-bar 29, so that the receptacle 3 completes its back step and comes again to the relative position of Fig. 1, discharging the cash contained in the last pocket filled. 110

If more than one deposit be made in any cash-receptacle before there is a delivery therefrom, such receptacle may slip on the spring 8, owing to the frictional connection thereof; but the tension of the spring will always be maintained sufficient to turn the wheel back for at least the space of one pocket. 115

Having thus fully described my invention, the following is what I claim as new therein and desire to secure by Letters Patent: 120

1. In a mechanical cashier the combination with a casing having an opening, of a rotary cash-receptacle adapted to receive and deliver cash through said opening, and adapted 125

- to discharge cash within the casing, said cash-receptacle being exposed at said opening so as to be engaged and operated by the operator's hand.
5. 2. In a mechanical cashier, the combination with a casing having a charging and delivery opening and an internal discharge-opening, of a cash-receptacle adapted to be rotated within said casing, indefinitely in one direction, and having pockets brought in such rotation, in coöperative relation with said charging and delivery opening and with said internal discharge-opening, said cash-receptacle being adapted to be operated directly by 15 the operator's hand, through said charging and delivery opening.
3. In a mechanical cashier, a plurality of independently movable denominational receptacles mounted on a common shaft and 20 each adapted to be directly engaged and moved by the operator's hand to render inaccessible the cash deposited in the receptacle, means tending to return each receptacle to deliver cash, a detent for preventing return movement of the receptacle and means for releasing such detent.
4. In a mechanical cashier, a casing having a charging and delivery opening, a rotary receptacle adapted to be engaged by the operator's hand through said opening to render inaccessible the cash deposited in the receptacle, means tending to return the receptacle, an escapement controlling such return in a 35 step-by-step manner, and means for controlling such escapement.
5. In a mechanical cashier, the combination with a casing having a charging and delivery opening, of a movable cash-receptacle adapted to be charged through said opening and 40 to deliver cash through said opening and means tending to move the receptacle to deliver cash, of an escapement controlling the delivery movement of said receptacle in a step-by-step manner and controlling means 45 for said escapement.
6. In a mechanical cashier, the combination with a rotary cash-receptacle rotatable indefinitely in one direction and a spring for turning same to deliver cash, of a connection between said spring and the cash-receptacle adapted to allow slip of one part relatively to the other, an escapement mechanism controlling the delivery movement of said receptacle in a step-by-step manner, and means for 55 controlling said escapement mechanism.
7. In a mechanical cashier, the combination with a rotary cash-receptacle, and a device tending to turn same to deliver cash but connected thereto by a frictional connection, of 60 a detent means for said cash-receptacle.
8. In a mechanical cashier, the combination with a rotary cash-receptacle and a spring tending to turn same to deliver cash but connected thereto by a frictional connection, of 65 a detent means for said cash-receptacle consisting of an escapement mechanism and controlling means therefor.
9. In a mechanical cashier, the combination with the casing having a charging and delivery opening and an internal discharge-opening, of a rotary cash-receptacle adapted to rotate within the casing and located with its face exposed at the charging-opening and adapted to be directly engaged and operated by the operator's hand through said opening, 70 and escapement means controlling the movement of the receptacle in one direction, the receptacle being freely rotatable indefinitely in the other direction.
10. In a mechanical cashier, the combination with the casing having an opening, of a rotary cash-receptacle exposed at the said opening and adapted to be turned in one direction by direct engagement of the operator's hand, and an escapement-controlling, 80 step-by-step, movement in the other direction on operation of the escapement by means other than the cash-receptacle and locking the receptacle against such movement in the other direction except upon such operation 85 of the escapement, and operating means for so operating the escapement.
11. The combination with the rotary cash-receptacle and cash-delivery-operating means for causing delivery of cash from said receptacle, of selector means governing the operation of such operating means and means operated by the cash-receptacle in its receiving movement to control the selector means, substantially as and for the purpose set forth. 90
12. The combination with the rotary cash-receptacle, adapted to be moved in one direction by the operator's hand to render the deposited cash inaccessible, and means for returning the receptacle to deliver the cash, 95 of a selector means governing the operation of the returning means and means operated by the cash-receptacle to control the selector means, substantially as and for the purpose set forth. 100
13. The combination with the rotary cash-receptacle, adapted to be moved in one direction by the operator's hand, and a spring for moving it in the reverse direction, of an escapement engaging with the cash-receptacle to control its movement in said reverse direction step by step and means for controlling said escapement, consisting of an operating device and means adapted to be interposed between such operating device and escapement. 110
14. In a mechanical cashier, the combination with the casing having a charging and delivery opening and an internal discharge-opening, of a cash-receptacle moving in proximity to said openings and adapted to present the money to said openings in such position that it will fall from said receptacle and be delivered through said openings by gravity. 115
